UNITED STATES PATENT OFFICE.

AARON HILL, OF NEAR LOS ANGELES, CALIFORNIA, ASSIGNOR OF ONE-FOURTH TO
RAYMOND IVES BLAKESLEE, OF LOS ANGELES, CALIFORNIA.

WIRE MATTRESS.

1,051,584.

Specification of Letters Patent. Patented Jan. 28, 1913.

Application filed March 7, 1912. Serial No. 682,093.

To all whom it may concern:

Be it known that I, AARON HILL, a citizen of the United States, residing in Los Angeles county, near Los Angeles, and 5 State of California, have invented new and useful Improvements in Wire Mattresses, of which the following is a specification.

This invention relates to wire mattresses for beds and the like; and it has for its object to provide improvements in such mattresses which will render the same superior with respect to maintenance of conformation, strength, durability, positiveness of action, comfort to the user and efficient 10 action with the stuffed mattress ordinarily employed in connection therewith; and which improvements will be generally superior in efficiency and serviceability.

The invention consists in the novel and 20 useful provision, formation, construction, association and relative arrangement of parts, members and features, all as hereinafter described, shown in the drawing and finally pointed out in claims.

25 In the drawing:—Figure 1 is a side elevation of a bed of the three-membered type provided with a wire mattress organized and constructed in accordance with the invention, a stuffed mattress being shown in position upon the wire mattress; and, Fig. 30 2 is an enlarged fragmentary perspective view of leading features entering into the construction embodying the improvements.

Corresponding parts in both figures are 35 denoted by the same reference characters.

Referring with particularity to the drawing, A designates the head frame member, B designates the foot frame member, and C designates the mattress frame member of a 40 bed of the three-member type, such members being connected by suitable joints D between the two former members and the side rails, e, of the mattress frame member.

F designates the wire mattress of the 45 mattress frame member, the same being connected with and supported upon the side rails, e, as at 3, at the ends of the wire mattress, in any suitable manner, the wire mattress being shown as provided with transverse end bars or rails 4 having up-standing 50 end pieces 5, each such bar or rail 4 with its end pieces 5 being connected by coil springs 6 with a supplemental transverse bar or rail 7 and the up-standing pieces 8 thereof. The 55 woven wire mattress body 9 extends between

the bars or rails 7, and a truss e is applied to the wire mattress body at each side edge of the same, extending between the upright end pieces 8 and connected at one or more points with the body 9 intermediate of such 60 end pieces. Preferably, said truss e comprises a suspension member 10 of wire, cable, rope or built-up formation, which, as shown in the drawing, may consist of a longitudinal wire strand core 10^a around which 65 is formed a closely wound helix 10^b of wire. Such construction, is, however, optional, and may be varied according to the nature and demands of service.

The suspension member 10 is normally 70 downwardly looped from its end portions which are connected with the upper ends of the end pieces 8, to its central portion where it is tangent to the central portion of the side edge portion of the woven wire mattress body 9, where the suspension member and such mattress body edge portion are bound together, as by tie-wires or a suitable wire, as the case may be, as at 11. Between the suspension member 10, and between the 75 tie-wires 11 and the end pieces 8, at intervals, extend suspenders 12 connected at their upper ends with the suspension member 10 and at their lower ends with the edge portions of the mattress body 9, which may be 80 reinforced by a longitudinal strand 13 of twisted wire cable, or any suitable substitute. These suspenders may be vertically arranged, or in part vertically and in part 85 slant-wise, to complete a stress-resisting 90 strong formation of the truss e. The provision of such truss e materially strengthens the wire mattress at the side edge portions, preventing the same from distortion and depression, and maintaining a true flat formation, or approximately flat formation at the 95 edges of the wire mattress, any strain imposed upon such edge portions of the mattress being taken up by the suspenders 12 and suspension member 10 of the truss e and 100 the tie-wires 11, the strain being finally imposed through the suspension member 10 upon the transverse bar or rail 7 and the end pieces 8 thereof, and thence through the coil spring 6 upon the transverse bar or rail 105 4 and end pieces 5 thereof to the side rails e of the bed frame which is of course rigid and non-yielding.

It is well known that the ordinary wire mattress has the tendency to give and sag 110

at the side edges, causing resultant breakdown in those portions of the mattress. Also, such give at the side edges tends to render the mattress uncomfortable to use.

- 5 The truss holds up the side edges, so that the depression resultant upon the weight of the occupant of the bed occurs between the side edges, as is proper, causing a comfortable fit of the mattress to the body of the occupant.
- 10 The employment of this truss results in increased durability, strength, and length of life of the mattress, and also serves to hold the stuffed mattress H in proper position against lateral displacement upon the wire mattress.

15 The use of the truss prevents the sagging of the mattress at the edge so as to pinch or bind the bedding or the person sitting or resting upon the edge of the bed, or the hands of the person making up or attending to the bed, between the side rail and the wire or stuffed mattress or both.

20 I am aware of the fact that means have been provided at the sides of wire mattresses for preventing slipping of the stuffed mattress, as above referred to; but I am not aware of the provision of any strengthening and reinforcing means, such as the truss e,

at the side edges of mattresses, in accordance with my invention as above disclosed. 30

Having thus described my invention, I claim and desire to secure by Letters Patent:—

1. A wire mattress provided at its side edge with a suspension member above the wire mattress and connected intermediate of its ends with the wire mattress and tangent thereto, and means with which the ends of the suspension member are connected in elevation above the wire mattress. 40

2. A wire mattress provided at its side edge with a suspension member above the wire mattress and connected intermediate of its ends with the wire mattress and tangent thereto, and means with which the ends of the suspension member are connected in elevation above the mattress; there being suspenders between the suspension member and the edge of the wire mattress. 45

In testimony whereof, I have signed my name to this specification in the presence of two subscribing witnesses.

AARON HILL.
